James Cochran, of Batavia, State of New York,
Letter Patent. 9825X

The schedule referred to in this Letter Patent & making
part of the same, containing a description in the words of the said
James Cochran himself of his Improvement in "Aard van Bass."

To all to whom these presents shall come,

Be it known that I James Cochran of Batavia in the County of
Seneca and State of New York, doth invent and make
of his improvement in "Aard van Bass"; and that the following is
a full and exact description thereof.

Fig 1. an draft a main bar, of sufficient length and size
of weight or cast iron with three feet two at the back and
sufficiently spread to keep the bar firm and steady. one at the
center end of the bar, made hollow.

Fig 2. short bar made straight or circular of any suitable
size & length, which may be cast on to the front standard
inward or outward. to the same as circumstances may require
the short bar being attached. The head pedestal and foot
may be kept in their proper positions by a spike 4 in the
back end of the short bar, made to fit into the hollow foot
5. in the front end of the main bar, from which the whole front
part of the Aard van may be easily disengaged for the purpose
of cleaning, sweeping, repairing or packing.

Fig 3. slide for the purpose of holding a rolling stock
steady, sliding in a groove in each side of the main bar,
about one-fourth of an inch in depth and half or two-thirds
the length of the bar, from the front end.

What I claim as my own invention and not previously
known in the above described improvement is a bar so construc-
ted that the front part may be disengaged for the purpose

of cleaving and sawing without disturbing that part which supports the wood for a fire. also a slice for the purpose of keeping the wood steady moving back and forward in a groove also by making the hole in the forward foot largest at the bottom and the strike smallest at the bottom, giving sufficient room for play that all the feet may adjust themselves to an uneven hearth also relieving the front feet, from the usual weight and pressure of common sledging.
